UNITED STATES PATENT OFFICE.

ROBERT R. GOLDSMITH, OF HARTFORD, CONNECTICUT.

WIRELESS RECEIVING APPARATUS.

1,091,127.

Specification of Letters Patent. Patented Mar. 24, 1914.

Application filed August 31, 1912. Serial No. 717,993.

To all whom it may concern:

Be it known that I, ROBERT R. GOLDSMITH, a citizen of the United States, and a resident of Hartford, in the county of Hartford and 5 State of Connecticut, have invented certain new and useful Improvements in Wireless Receiving Apparatus, of which the following is a specification.

The object of this invention is to provide 10 a set of receiving instruments for use with wireless transmission of intelligence which is simple, compact and self contained, and the parts of which are readily accessible.

In the drawings—Figure 1 is a side view 15 of my complete receiving set. Fig. 2 is a simple vertical section thereof. Fig. 3 is an end view. Fig. 4 is a cross sectional view on the line α α looking in the direction of the arrow a . Fig. 5 is a cross sectional view on 20 the line α α looking in the direction of the arrow b . Fig. 6 is a detail view of the slide. Fig. 7 is a diagrammatic view showing the buzzer circuit.

The embodiment of the invention illus- 25 trated is designed for use in connection with wireless telegraphy, but it is equally as useful in connection with wireless telephony.

Referring to the drawings 1 denotes a light case within which is mounted the tun- 30 ing coil 2 wound upon the paper tube 3. Fitted into adjacent corners of the case, which is cut away at these points, are curved metallic strips 4, 4 longitudinally slotted as at 5 through which a pair of arms 6, 6 se- 35 cured to a rubber button 7 project. A friction plate 8 curved to fit the underside of the metallic strips is notched to receive these two arms, at the end of one of the arms is at- 40 tached a yoke 9 supporting a roller 10 which is adapted to rest upon and coöperate with the tuning coil. The other arm acts as a guide for this roller, and a spring 11 lo- 45 cated between the yoke and the friction plate holds the parts in position so that the complete structure which I will term the “slide” can be moved freely along the metallic strip by means of the button. This produces a smoothly acting slide, free from any danger of cramping or sticking, and 50 sufficiently stiff to stay in any position of ad-

justment. At one end of the casing one terminal of the coil is connected to a binding post 12 to which the aerial wire is attached.

A rotary condenser 13 of usual construc- 55 tion, but adapted in size to fit within the tuning coil, is mounted on one of the end plates 14 of the casing, the two parts of the condenser being electrically connected with ends of the slide strips by the act of securing the end plate in position; a handle 15 is pro- 60 vided with which the movable member of the condenser can be operated.

On the opposite end plate 20 various additional parts of the receiving apparatus are mounted in such a compass that they are 65 contained within the hollow tuning coil, this end plate being preferably made of insulating material to provide a suitable support. Secured to the inner surface of this end plate 20 is a frame work to which the va- 70 rious parts of the apparatus, except the main condenser, are secured. It comprises the disk 60 secured to the end plate, posts 48, 62 and the disk 61 secured to the ends of the posts; post 62 is a ground post having con- 75 nected to it on the outside of the end plate the binding post 32. The parts of the detector 25 are conveniently mounted on the door 22 and hinged to the end plate 20 to make it accessible for adjustment. The de- 80 tector is connected by the wire 27 through the condenser 28 to the ground post 62.

30 denotes a switch connected through the conductor 31 with one of the slide strips 4. This switch in its “on” position engages the 85 terminal 29 of the detector circuit; in its “off” position (indicated in Fig. 4) it connects with the ground post 62 cutting-out the detector. The telephone receiver T is connected to the binding post T' T'' on the 90 front of the end plate 20, the former being connected with the detector and the latter with the ground. In other words the telephone receiver is connected around the condenser 28.

In order to test the detector I have pro- 95 vided a tell-tale device in the nature of a buzzer, operated by a battery with a nor- mally open circuit. In detail the buzzer comprises a frame struck up from a piece 100

of sheet metal having a base 41, an upstanding lug 42 to which the magnet 43 is attached and oppositely disposed arms between which a thin metallic reed 45 is stretched 5 passing adjacent to the pole of the magnet. 40 is an adjustable point arranged on the other side of the reed opposite the magnet core. I have provided means for changing the tone of the reed comprising a post 49 adjacent to one of the arms 44 against which a screw 50 threaded in this arm engages. By this means the arm can be sprung to vary tension of the reed and consequently its vibration. This form of buzzer is especially 15 well adapted for use with a wireless detector. 46 denotes a battery which may be supported by a clip attached to the post 62. An exposed terminal of the battery is in electrical contact with the post 48 which thus 20 becomes one terminal of the battery circuit, the other side of the battery being connected to the magnet and thence to the spring terminal 47 normally standing away from the post 48 so as to break the circuit, 25 but in position to be acted upon by the insulated tip 35 of the switch spindle when it is moved longitudinally with the switch in "on" position, to close the circuit and sound the buzzer. A condenser 66 is connected 30 between the buzzer circuit and ground.

One of the slide conducting strips 4 connects one terminal of the main condenser 13 with the switch 30 through the strip 31. The other slide strip 5 connects the other 35 side of the condenser 13 with the ground post 62 through the strip 31½. As a result of this construction, it will be seen that all of the operative parts of the mechanism are inclosed within the tuning coil, the rotary 40 condenser at one end with nothing but its operating knob showing on the outside of the casing, and the detector, condenser, buzzer and circuit connections are inclosed in the other end of the coil with nothing showing 45 except the detector switch buttons, telephone binding posts and the aerial and ground binding posts. The slides are fitted in the curved slide plates, and the operating buttons conform closely to the contour of 50 the casing.

The apparatus is complete in all its details and constitutes a highly efficient receiving apparatus, and it is peculiarly adapted for use in small stations, on boats, aeroplanes and for other uses where lightness 55 and compactness are necessary.

I do not wish to be understood as limiting myself to the exact structure or assembly of parts here illustrated and described, as 60 I am aware that various modifications in assembly can be utilized.

I do not wish to be understood that the circuit connections are limited to those shown in the drawings.

I claim as my invention:

1. In a wireless receiving apparatus a casing, a hollow tuning coil fixedly secured within the casing and open at both ends, closures for the ends of said casing and coil, a condenser mounted on one closure and located within the coil, a detector, circuit connections and a detector switch mounted on the other closure and located within the coil, slides arranged in operative relation to the coil and movable longitudinally thereof, 70 supports for said slides in electrical connection therewith, said supports electrically connecting said condenser with the detector and ground terminals.

2. In a wireless receiving apparatus a 80 casing and a tuning coil located therein, a closure for one end of said casing, a condenser supported by said closure and located within the coil, an operating handle for the condenser; a closure for the opposite end of 85 said casing, a detector mounted on the inner face of said closure, a ground terminal and a switch terminal carried by said closure, electrical connections between said terminals and the terminals of the condenser, a 90 circuit from the ground terminals to the other switch terminal and including the detector, a switch controlling said detector circuit, an operating handle for the switch located on the front of said closure, said circuit connections and switch being supported 95 upon said closure and located within said coil.

3. In a wireless receiving apparatus a casing, a tuning coil located therein, a closure 100 for one end of the casing, a condenser supported by said closure and located within the coil, an operating handle for said condenser; a closure for the opposite end of 105 said casing, a detector mounted thereon, a ground terminal mounted thereon, a switch mounted thereon, a circuit including said detector and switch, a telephone-receiver-circuit, a condenser located therein, said detector circuit and telephone-receiver-circuit 110 being arranged within the coil.

4. In a wireless receiving apparatus a casing, a hollow tuning coil mounted within the casing, said casing having a plurality of longitudinal openings, strips of conducting 115 material fitting in and closing said opening and extending from one end of the case to the other, said conducting strips being longitudinally slotted, slides arranged in co-operative relation with the coil with stems extending through said slots, operating buttons secured to said stems, an end plate to close one end of the casing and coil, a condenser carried by said end plate and adapted to fit within the coil, condenser terminals 120 arranged opposite to the ends of said conducting strips and adapted to make electrical contact therewith when said end plate

is fitted in place; an end plate adapted to close the opposite end of the casing and coil, a detector mounted on the inner surface of said end plate, circuit connections therefor, and circuit terminals arranged opposite to the other ends of the conducting strips and adapted to make electrical contact therewith when the end plate is in position, the condenser, detector and the circuit connections being inclosed within said coil and 10 casing and concealed thereby.

ROBERT R. GOLDTHORP.
